UNITED STATES PATENT OFFICE.

CHARLES F. HEINE, OF MODOC, ILLINOIS.

DESIGN FOR A WEED-CHAIN HOOK.

SPECIFICATION forming part of Design No. 32,485, dated April 10, 1900.

Application filed March 16, 1900. Serial No. 8,999. Term of patent 14 years.

To all whom it may concern:

Be it known that I, CHARLES F. HEINE, a citizen of the United States, residing at Modoc, in the county of Randolph and State of Illinois, have invented and produced a new and original Design for a Weed-Chain Hook; and I do hereby declare the following to be a full, clear, and exact description of the invention, such as will enable others skilled in the art to which it appertains to make and use the same.

This invention relates to a design for weed-chain hooks for agricultural implements, of novel formation and outlined and adapted to be attached to any beam.

The design consists of a frame of $\square$ form, constituting a clamp member and a hook, forming a continuation of a leg of the frame and projecting outward therefrom, the hook and frame being in the same plane.

The design consists of the novel outline and configuration which hereinafter will be more particularly described, and shown in the drawings, in which—

Figure 1 is a perspective view, and Fig. 2 a front view, of the hook.

Corresponding and like parts are indicated in both views of the drawings by the same

reference characters and the same are used in the description to designate the parts when making reference thereto.

The frame consists of the horizontal bar 1 and the vertical bars or legs 2 and 3, extending in parallelism. The leg 3 has a threaded opening 4 to receive a clamp-screw. (Not shown.) The leg 2 is longer than the leg 3 and its lower end curves outwardly and upwardly, forming the hook 5, to which the drag-chain (not shown) is attached. The frame forms a clamp member by means of which the device is attached to a beam and the hook 5 receives the drag-chain. The bars of the frame are rectangular in cross-section, whereas the cross-sectional outline of the hook is round. The hook and frame are in the same plane.

Having thus described the invention, what is claimed as new is—

The design for a weed-chain hook, substantially as herein shown and described. 50

In testimony whereof I affix my signature in presence of two witnesses.

CHARLES F. HEINE. [L. S.]
